UNITED STATES PATENT OFFICE

ARTHUR A. JOHNSON, OF NEW YORK, N. Y., ASSIGNOR TO UNDERWOOD ELLIOTT FISHER COMPANY, OF NEW YORK, N. Y., A CORPORATION OF DELAWARE

MANIFOLDING DEVICE

Application filed March 24, 1922. Serial No. 546,321.

This invention relates to manifolding equipment and more particularly to the provision of means for holding and controlling the carbon or other manifolding material with 5 relation to multiple-ply webs or worksheets of indefinite length.

One of the more important features of this invention is the provision of a carbon sheet holder for use with fan-folded webs, which 10 holder is simple in construction, and therefore can be produced at small cost. It is also capable of being made light in weight so that the carbon unit can be mounted upon the web, that is, so that it can be supported 15 directly by or ride upon the worksheet or web, and simple in operation so that it can be used without study or practice by persons of ordinary ability.

In addition to the above advantages, the 20 carbon sheet holder of this invention is advantageous in that the holder with its carbon leaves forms a unit that can be used with any style or type of writing machine or device, including typewriters, recorders, manifold- 25 ing registers, writing tablets etc., and furthermore requires no physical or structural connection to the machine as will hereinafter be more particularly pointed out.

The carbon-sheet holder illustrated herein 30 may be made of a sheet of material such as celluloid, fiber, or metal having side strips and arms projecting from the side strips and free at their ends from the opposite side strip. The arms which are adapted to be placed be- 35 tween the leaves or folds of a fan-fold web carry and hold the carbon sheets in position to transfer onto the under leaves the writing which is performed on the uppermost leaf. When the writing of a portion of the webs, 40 or a form as it is called, is completed the carbon sheet holder with its carbon-sheets is moved relative to the web so as to bring the carbon sheets into position to cooperate with the next form. This movement withdraws 45 the carbon sheets from the form previously written so that this form may be severed from the continuous web. The severing may be performed by a knife but this is not es- 50 sential since weakened division lines between the forms may facilitate tearing.

In moving the carbon sheets along the web to cooperate with the next form, the new position of the carbon unit or rider may be determined by bringing a predetermined point on the carbon molder into register with 55 a predetermined point on one of the succeeding forms and under some conditions this mode is preferable. It is, however, not essential since the position of the ends of the carbon sheets may easily be seen through the 60 uppermost leaf of the pile when the paper is transpicuous, which is usually the case.

There is also herein disclosed a tablet which 65 is adapted for manuscript work and with which the carbon unit or rider is combined.

Other features and advantages will herein- 70 after appear.

In the accompanying drawings:

Figure 1 is an inverted perspective view 75 showing one embodiment of my carbon sheet holder apart from the carbon leaves.

Figure 2 is a sectional side view showing 75 diagrammatically how the carbon sheets or leaves may be attached to their holder arms and interposed between the plies of the fan-fold web, and showing the holder and carbon leaves forming the unit mounted on or supported by the worksheet.

Fig. 3 is a perspective view of the writing tablet feature of this invention combined 80 with the carbon sheet holder and carbon sheets or leaves shown in Fig. 1.

Fig. 4 is a detail view showing a writing 85 platen with means thereof for controlling the position of the carbon sheet holder.

The carbon sheet holder is illustrated here- 90 in in the form of a flat plate or sheet 10, which may be made of celluloid, fiber, metal, or even cardboard, so as to be light in weight. By stamping or other suitable operation, parts of the sheet 10 are cut-out to provide separate arms 11 each projecting from one of the sides 12 of the sheet and having free ends 13 spaced from the opposite side 12. 95 Preferably, alternate arms 11 extend from opposite sides 12 and the number of arms provided depends on the number of carbon sheets needed. The arms alternate with slots to accommodate the plies of web. 100

At the ends of the plate, strips 14 are left to connect the sides 12 to each other.

The arms 11 are adapted to be attached to and hold carbon sheets 15 and with the carbon sheets they are placed between the leaves, or in other words in folds of the fan-fold web as shown in Fig. 2. In this position the carbon sheets are adapted to transfer upon the face of the under leaves any writing or typewriting that may be done 10 on the upper leaf A.

Each side fold of the web passes around the end 13 of one of the arms 11 between the end 13 and the wall 16 of that part of the 15 side 12 adjacent the end 13. By this means the web is guided and maintained in proper position relative to the holder and the carbon sheets carried thereby. The plies of the web pass individually through the series of 20 slots, which alternate with the arms 11, as seen at Figure 2. To further guide the web, the rear end strip 14 is provided with a slot 17 through which the entire web passes. This slot 17 guides the layers or folded leaves of 25 the web so that they pass between the arms 11 in proper alinement. This slot also serves the function of preventing accidental movement of the carbon sheet holder relative to the web by producing a rather abrupt bend 30 in the web at this point. However, it is not in all cases essential that the slot 17 be provided for the purposes of preventing accidental movement of the holder and of supporting 35 the holder on the web, because these functions are performed by the arms 11. When the latter are made sufficiently resilient they engage opposite sides of the layers or folded leaves of the web and yieldingly prevent movement of the holder along the web and 40 support the holder on the web. It should be noted that due to the flexibility of the carbon sheet holder the parts, in practice, will not appear exactly as shown in Fig. 2 in which, for the sake of simplicity, the holder is 45 shown as though it were rigid. As a matter of fact the arms 11 bend to accommodate themselves to the passage of the webs through the slots in a substantially straight line through the holder except to the rear of the 50 carbon arms where the webs pass through the slot 17 when the holder is being moved. At the front the top sheet A of the web, passes through the space or slot between the forward arm 11 and the end strip 14 and 55 below the same. This arrangement of the front end strip 14 across the face of the web acts to prevent the operator from writing on the portions of the web in which the carbon sheet holder is located. The leading 60 edge 18 of the strip 14 also acts as an index, to which the top of the form is brought when the carbon holder is retracted, and when this is done the ends of the carbon sheets are alined with bottom of the form which is to 65 be written upon, so that the previously writ-

ten form may be severed from the one to be written upon. The invention is not limited to fan-fold webs.

The carbon sheets may be held to the arms 11 by any suitable means such as paper fasteners, etc. However, it is at present preferred to provide a slot 19 in each of the arms 11 through each of which the end of a carbon sheet is passed after it has been wrapped around the arm 11. The ends of the carbon sheets are thus clamped under the body of the carbon sheet.

As shown in Fig. 3 the tablet 20 may comprise a board or other suitable base across which the continuous strip is passed. The forward end of the tablet is provided with a knife 21 under which the end of the web is located. The carbon sheet holder is supported upon the tablet, as shown, but it may be supported directly by the web, if desired.

As shown in Fig. 3 the tablet is gouged out at 22 to enable the sides 12 to be easily grasped when it is desired to shift the carbons. Directly in front of the gouged portion there is provided a pair of stationary pins 23 for holding or detaining the carbon holder adjacent the gouged portions, while the web is being drawn through the carbon unit. The pins are placed one at each side of the web, to engage the oppositely projecting ends of the 95 carbon unit or web rider. The web is drawn between the pins or stops.

In operation, the carbon sheets with their arms are interleaved with the fan-fold web, or in other words the carbon unit is mounted 100 upon the web, and then the carbon-unit or rider is moved rearwardly upon the web until the end of the shortest carbon sheet is in line with the bottom of the first form. The pile is then placed under the knife 21 so that the bottom of the first form is alined with the knife. The surplus lengths of the carbon sheets are then cut off. After the form is written upon, the operator grasps the multiple ply web and moves it forwardly from under the knife so that the end can be grasped. With one hand holding one of its sides and with the other hand holding the web at the front, the operator moves the carbon rider 105 rearwardly along the web until it is observed that the ends of the carbon sheets are in line with the bottom of the next form. The previously written form, which has been freed of the carbon sheets, is then severed along the knife 21, or, if a knife is not provided, then simply by tearing the web along a perforated line.

If the pins 23 are provided, as is the case in the form shown in Fig. 3, then it is simply necessary for the operator to pull the web forwardly when shifting the carbon sheets, the carbon unit or rider being then held in position against moving with the web by the pins 23 engaging the forward edge 18 of the carbon holder or unit.

In using the carbon sheet holder or rider with a flat platen typewriting machine substantially the same procedure is followed.

It should be noted that the carbon sheet rider is particularly adapted for use with webs which are to be written upon directly on the desk and at places where a machine could not be used and that it requires no special platen or other mechanism in its 10 operation.

The carbon sheet holder being light in weight is readily susceptible of being supported by a free stretch of web and by its own action is held to the web in any position in which 15 it may be placed.

It will be seen that the flexible carbon sheet unit, with its series of slots through which the plies of web are individually threaded, forms a web rider which may be slipped along the 20 web, or which may be held stationary while the web is drawn therethrough.

Generally speaking, there is provided a band or wristlet through which the workstrip or web runs, and which also rides upon the 25 workstrip, and advances therewith, when the latter is advanced line by line during the writing of a page. This is in the nature of a unit, said unit including carbons which interleave with the workstrips or web-plies. The carbons 30 are connected to one another, so that all may move as a unit. The connection obviously cannot go right through the workstrips, but is positioned beyond the borders of the workstrips. In this instance the connection at each side of the webs consists of 35 the side member 12. To these side connections all of the carbons are joined by means of arms 11 (since the carbons are attached to said arms, and since the arms are integral with the side members 12). The members 12 are joined to each other by the integral cross-bars or end strips 14. It will be seen that 40 through the connections 12, 12, 11, 11, 11, and the cross-bars 14, all of the carbons are joined 45 to one another, making a unit which can slip along the workstrips. The carbons may be separated sufficiently to permit the workstrips to be introduced or threaded between the carbons while the latter remain connected 50 to one another. The unit girdles the workstrips.

Variation and modifications may be resorted to within the scope of my invention and portions of the improvements may be used 55 without others.

I claim as my invention:

1. A carbon sheet holder comprising a plate having two sides and integral arms extending from each side toward the other, and free 60 of the opposite side.

2. For use with a strip of web of indefinite length having a plurality of layers and a plurality of carbon sheets to be located between the layers of the web; a holder from which the 65 carbon sheets trail, said holder extending

transversely of the web and having means engaging the web for supporting the holder on the web and said holder being movable along the web to bring the carbon sheets to a new position after the part of the web covered by the carbon sheets has been written upon. 70

3. For use with a strip of web of indefinite length having a plurality of layers and a plurality of carbon sheets to be located between the layers of the web; a holder from which the ends of the carbon sheets trail, said holder being supportable on and movable along the web to bring the carbon sheets to a new position after the part of the web 80 covered by the carbon sheets has been written upon, said holder having means for holding the layers of the web together and for causing the layers to move into alinement during the movement of the holder along the 85 web. 90

4. A carbon sheet holder movable along a pile of webs of indefinite length and having means for holding carbon sheets between the webs of the pile and independently supporting the holder on the pile of webs. 95

5. A carbon sheet holder movable along a pile of webs of indefinite length and having a plurality of sets of arms, the arms of one set being secured to and projecting from one side thereof and the arms of the other set being secured to and projecting from the other side thereof, said arms holding carbon sheets between the webs of the pile and holding the holder to the pile of webs. 100

6. A carbon sheet holder movable along a pile of webs of indefinite length and having means for holding carbon sheets between the webs of the pile and also having means for causing the webs on passing through the 105 holder to follow a tortuous course whereby the holder and webs are held together frictionally against unintentional relative movements.

7. A carbon sheet holder movable along a pile of webs of indefinite length, comprising a strip; an arm secured at one end to the strip and free at its other end; a second strip; an arm secured at one end to the second strip; and means for connecting the strips together with the free end of one of the arms adjacent the strip to which the other arm is secured, said arms holding carbon sheets between the webs of the pile and supporting the holder upon the pile of webs by respectively 115 engaging opposite surfaces of a portion of the pile of webs. 120

8. A device adapted to be moved from position to position along a fan-fold web comprising a plurality of sets of oppositely extending arms adapted to extend between the folds of the web, the sets extending into the folds from opposite sides and each arm of each set receiving the end of a carbon sheet and holding said sheet in a fold of the web; 130

- and guide surfaces on the holder in position to engage the web along the lines of fold and thereby guide the movement of the holder along the web.
5. 9. A carbon sheet holder movable along a pile of webs of indefinite length, having means for holding carbon sheets between the webs of the pile, said holder being sufficiently light weight to be supported by a free stretch 10 of the pile of webs which act as a track in guiding the movement of the holder therealong.
10. A carbon-carrier for enabling a typewriting machine to manifold a multiple-ply 15 work-web, comprising a sheet of flexible material having a series of transverse slits therein to form carbon blades therebetween, each of said slits arranged to have a single ply of a plurality of superposed plies of workweb 20 threaded therethrough, and brought forwardly, so as to overlie a carbon, the composite pack to be entered beneath the platen from the rear of the machine and fed upwardly therethrough during typing.
25. 11. A web riding carbon-carrier comprising an elongated sheet of flexible material having a series of transverse openings adjacent its mid-section and carbon-sheets attached to portions of said sheets between said openings, 30 the plies of a multiple-ply web being threaded through said openings, the web and carrier being relatively shiftable to strip the carbons.
12. For use in a typewriting machine having a platen, a flexible carbon-stripper having 35 a series of transverse slits through which work-webs are threaded, the stripper being carried by the work-webs, and carbons attached to said stripper and interleaved between the work-webs, the stripper and the 40 webs being relatively shiftable to strip the carbons to shift them to new positions along the work-webs.
13. For use in a typewriting machine having a platen, a flexible carbon-stripper having 45 a series of transverse slits through which work-webs are threaded, the stripper being carried by the work-webs, and carbons attached to said stripper and interleaved between the work-webs, the stripper and the 50 webs being relatively shiftable to strip the carbons to shift them to new positions along the work-webs, the leading end of the stripper extending sufficiently in advance of the slits to form a backing for the carbons, said carbons extending from said slits toward said leading end.
14. A carbon-carrier comprising a sheet of flexible material having a plurality of transverse openings therein, and between which 60 carbons are fixed and interleaved with work-plies led through said openings, and means for positively holding said carrier so as to maintain said carbons in position, during shifting operations between the latter and the 65 work-plies.
15. A carbon-carrying girdle to ride upon a set of workstrips in a writing and manifolding implement, with the workstrips extending through and the carbons trailing from the girdle, so that the carbons and workstrips may be relatively shiftable, said riding girdle being wider than the workstrips, and having means positioned beyond the opposite side edges of the enclosed workstrips, and confining the latter, for connecting one carbon 70 to another in a manner to admit of endwise insertion or threading of the workstrips between the connected carbons, and said girdle including a stripper member, for engagement with a stop upon the writing implement, to restrain the girdle and carbons against movement while the workstrips are advanced therethrough. 75
16. The combination with a stationary member, of a carbon-carrier in the form of a web-rider extending across the web and having a plurality of transverse openings and transverse members adjacent thereto, from which carbon-sheets may trail, said carrier arranged to have the plies of a plurality of 80 continuous work-sheets threaded through said openings and interleaved with said carbon-sheets, said carbon-carrier movable to trail said carbon-sheets in the direction of the length of the web, and including means to cooperate with said stationary member at the stripping operation, to restrain said carrier from movement while said work-sheets are being drawn through said openings to bring the last-used portion thereof beyond the carbon-sheets. 85
17. A carbon-carrying girdle formed to ride upon a set of workstrips in a writing and manifolding implement, with the workstrips extending through and the carbons trailing from the girdle, so that the carbons and workstrips may be relatively shiftable, said riding girdle being wider than the workstrips, and having means positioned beyond the opposite side edges of the enclosed workstrips, and confining the latter, for connecting one carbon to another in a manner to admit of endwise insertion or threading of the workstrips between the connected carbons. 90
18. A web-rider formed to engirdle the web and supportable by the web, said rider having means for holding together a plurality of carbon-sheets interposed with work-strips forming the web, for movement of said web-rider and carbon-sheets together with the work-strips, and also for independent movement of the web-rider and carbon-sheets relative to the work-strips, a support for the work-strips for writing purposes, and means on the writing support operative to restrain the rider and carbon-sheets against advancing movement when the work-strips are independently moved to place a fresh portion of the work-strips over the carbon-sheets, said restraining means permitting retrograde 95
- 100
- 105
- 110
- 115
- 120
- 125
- 130

- movement of the work-strips, rider and carbons together.
19. A web-rider from which may trail a set of carbon-leaves interleaved with plies of a multiple-ply web of indefinite length, with the carbon-leaves trailing from a portion forming a part of said rider, said part provided with a series of slots through which the web-plies are individually threaded, said rider formed for mounting upon the web to be supportable thereby, said rider movable along and engirdling the web to be guided thereby. 5
20. A web-rider from which may trail a set of carbon-leaves interleaved with plies of a multiple-ply web of indefinite length, with the carbon-leaves trailing from a portion forming a part of said rider, said part provided with a series of slots through which the web-plies are individually threaded, said rider formed for mounting upon the web to be supportable thereby, said rider movable along and engirdling the web to be guided thereby, and stationary means to restrain the rider against movement upon the web while the web 10 is being drawn through the rider. 15
21. A web-rider from which may trail a set of carbon-leaves interleaved with plies of a multiple-ply web of indefinite length, with the carbon-leaves trailing from a portion forming a part of said rider, said part provided with a series of slots through which the web-plies are individually threaded, said rider formed for mounting upon the web to be supportable thereby, said rider movable along and engirdling the web to be guided thereby, and stationary means to restrain the rider against movement upon the web while the web 25 is being drawn through the rider, the rider formed to project from opposite side edges of the web, and said restraining means including stops engaging the opposite projecting portions of the rider, the web being drawn between said stops. 30
22. For use in a typewriting machine having a platen, a flexible carbon-stripper having a plurality of transverse openings through which work-webs are threaded, the stripper being carried by the work-webs and adapted to trail carbons which are interleaved between the work-webs, the stripper and the webs being relatively shiftable to strip the carbons to new positions along the work-webs. 45
23. For use in a typewriting machine having a platen, a flexible carbon-stripper having a plurality of transverse openings through which work-webs are threaded, the stripper being carried by the work-webs and adapted to trail carbons which are interleaved between the work-webs, the stripper and the webs being relatively shiftable to strip the carbons to new positions along the work-webs, the leading end of the stripper extending sufficiently in advance of the openings to form a 55 backing for the carbons, the carbons extend- 60
- ing from said openings toward said leading end.
24. As a new article of manufacture, a set of superposed carbon-sheets trailing from a light web-girdle and forming a unit therewith for both riding upon a work-web and for relative movement between the unit and the web, for stripping the carbons, said unit including portions which project beyond the web and whereby the unit may be controlled during the carbon-stripping operation. 70 75
